(57) **CLAIM**

The ornamental design for a tool tray for interactive surface, as shown and described.

DESCRIPTION

FIG. 1 is a top perspective view of a tool tray for interactive surface showing our new design, wherein the tray is angled downward from the panel at about 17 degrees; FIG. 2 is a front elevation view of the tool tray for interactive surface showing our new design;

FIG. 3 is a back elevation view of the tool tray for interactive surface showing our new design;

FIG. 4 is a top plan view of the tool tray for interactive surface showing our new design;

FIG. 5 is a bottom plan view of the tool tray for interactive surface showing our new design;

FIG. 6 is a left side elevation view of the tool tray for interactive surface showing our new design; and,

FIG. 7 is a right side elevation view of the tool tray for interactive surface showing our new design.

The broken lines depict unclaimed structure that forms no part of the claimed design.
